CLAIM

(62) Division of application No. 29/579,470, filed on Sep. 30, 2016, now Pat. No. Des. 836,572.

The ornamental design for a target profile for a physical vapor deposition chamber target, as shown and described.

(51) **LOC (12) Cl.** 13-03

DESCRIPTION

(52) **U.S. Cl.** **D13/182**

FIG. 1 is a perspective view of a target profile for a physical vapor deposition chamber target, showing our new design;

(58) **Field of Classification Search**

FIG. 2 is a top plan view thereof;

USPC D13/182; D15/144.1, 144.2, 199

FIG. 3 is a bottom plan view thereof;

CPC H01L 21/67742; H01L 21/0226; H01L

FIG. 4 is a right side elevation view thereof;

21/02263; H01L 21/02266; H01L

FIG. 5 is a left side elevation view thereof;

21/02269; H01L 21/02271; H01L

FIG. 6 is a front elevation view thereof;

2224/75186; H01L 2224/761185; H01L

FIG. 7 is a back elevation view thereof; and,

2224/76186; H01L 2221/68363

FIG. 8 is an enlarged cross sectional view taken along line 8-8 in FIG. 2.

See application file for complete search history.

The dashed lines in FIGS. 1-8 represent disclaimed subject matter and form no part of the claimed design.
